(57) **CLAIM**

The ornamental design for a hand truck as shown and described.

DESCRIPTION

FIG. 1 is a front perspective view of a hand truck showing our new design;

FIG. 2 is a rear perspective view thereof;

FIG. 3 is a front elevation view thereof;

FIG. 4 is a rear elevation view thereof;

FIG. 5 is a right-side view thereof;

FIG. 6 is a left-side view thereof;

FIG. 7 is a top view thereof;

FIG. 8 is a bottom view thereof; and,

FIG. 9 is a front view showing a hand truck in condition of use.

The broken lines in the drawings depict environment and form no part of the claimed design.
